PROCESS FOR TREATING HYDROCARBON OILS

Ernest Wayne Rembert, Plainfield, N. J., assignor
of three-fourths to Tide Water Oil Company,
Bayonne, N. J., a corporation of New Jersey

Application July 22, 1932, Serial No. 623,977

11 Claims. (Cl. 196—67)

This invention relates to an improved method of treating mineral oils and similar material in continuous process, including operations in which thermal decomposition and recombination of hydrocarbons are effected in vapor phase to produce oils or liquids containing compounds of the same or different chemical series from those treated, and more especially to produce lower boiling oils and liquids, such as motor fuel products, gasoline, and the like. A particular application of the invention is in the production of motor fuel material having excellent anti-knock properties. The invention also relates to operations for the purpose of separating mineral oils and similar materials into classes of constituents having definite and predetermined boiling ranges, for the production of finished and semi-finished oils, in connection with the thermal decomposition and recombination step.

The invention may be regarded, without limitation, however, as constituting improvements in process over an invention described in my Patent No. 1,892,534, dated December 27, 1932. The materials for which this improved process is specifically suitable are mineral oils from any source. Such oils include crude oils and other residual-containing material, including topped crudes such as crudes from which the gasoline has been removed, and reduced crudes, which include crudes from which all or some of the normally distillable constituents have been removed, and which range from heavy fuel oils to light residues. By "residual-containing material" is meant oils containing or composed of high-boiling hydrocarbons which can not readily be vaporized without cracking, or in ordinary distillation, the remainder that does not go overhead as a distillate. Distillates of any nature, such as naphthas, kerosenes, gas oils and the like, are also suitable for treatment by this improved process, as well as mixtures of these with residual-containing materials.

The object of this invention is to provide improvements in process for the conversion of relatively heavy hydrocarbons, including distillates and materials containing residuals, for the production of lower-boiling materials in an economic and efficient manner.

One of the objects of this invention, in common with that of my Patent No. 1,892,534, is to provide for the production of low-boiling hydrocarbons, suitable for use as a motor fuel, from higher boiling hydrocarbons, in such a manner that no solid coke need be formed in the apparatus, and only a minimum amount of free carbon or lampblack, such an amount of free carbon being de-

pendent on the nature of the material to be converted.

A further object is the production of a motor fuel containing relatively large amounts of aromatic hydrocarbons or other hydrocarbons having good anti-knock qualities, for example, such as naphthenes or hydrocarbons of an unsaturated nature having similar qualities. Such a motor fuel, after suitable treatment, may be blended with other motor fuels for the production of a very satisfactory anti-knock gasoline, or may be used without blending as an improved gasoline.

Objects of this invention are to bring the material to be converted to a temperature high enough for conversion in a relatively infinitesimal time, to maintain this temperature for an optimum reaction time, and thereupon to stop the conversion reaction practically instantaneously by an intimate mixing with a cooling material such as charging stock, together with, preferably, a cool oil recovered from a later step in the process, to remove in a subsequent operation any lampblack and/or heavy oil fog, and to separate out the liquid material and to deliver a clean vapor for subsequent fractionation.

Another object, as in my prior invention, is to control the reaction time and the reaction temperature in a very definite and precise manner, so that the extent of conversion or cracking will be that desired and so that there will be definite control of the nature of the compounds that are formed.

Another object of this invention is to obtain the highest yields of material suitable for motor fuels and to limit the formation of tar and the gas loss to the least possible.

Another object of this invention is to obtain substantially complete conversion of distillate-charging stocks into motor fuel and gas, the amount of gas being held at a minimum.

A further object, as in my patent, is to crack hydrocarbons in such a manner that substantially no overcracking shall take place.

Another object is to convert residual-containing materials into low-boiling hydrocarbons with remarkably little production of tars or fuel oils.

Another object is to provide a process of improved flexibility of operation, to the end that without any change in the construction of the equipment it will be possible to obtain motor fuels of various types by controlling the reaction time and reaction temperature, while also can be obtained a plurality of products, the products not necessarily being limited to motor fuels, the eco-

nomical production of gas oil and/or fuel oil being contemplated.

5 A further object is to provide improvements in process with which it is possible to remove the natural gasoline from crude oil, and at the same time crack the heavier distillates contained in the crude oil. In such an operation, the excess heat required for the cracking step is used to supply the heat necessary for the vaporization 10 of such gasoline, and also, if desired, heavier distillable constituents or fractions.

15 Another object is to eliminate shut-downs, due to coking, plugging or any other causes.

15 Another object of this invention is to provide improvements in process suitable for the treatment of hydrogen-poor stocks, which give rise to the formation of lampblack when such materials are converted to low-boiling hydrocarbons.

20 A specific object or objects of this invention are to insure the delivery of a clean vapor to the fractionating equipment by the wetting out and removal of lampblack and the separation of any entrained heavy material.

25 Another specific object of the invention is to make the amount of charging stock used for the quick cooling of the reaction product independent of the amount of cooling to be accomplished, this being made possible by the re-circulation of liquid material obtained from a subsequent 30 stage of the operation, after cooling such liquid material.

35 A further object of this invention is to provide a more economical operation, in which gasoline contained in the tall gas formed is recovered in the feed stock or a stock withdrawn from the operation and returned to the unit, the heat necessary for the removal of the gasoline recovered to be supplied by the sensible heat in the reaction products.

40 Another object of this invention is to provide an improved process for the cracking of oils, with which it is easily possible to crack a material of any predetermined desired boiling range to be selected from the materials contained in a crude 45 mineral oil, when such a crude oil serves as raw material for the process.

45 Another object of this invention is to provide a method advantageous for the reforming of a light distillate for the production of anti-knock 50 gasolines and motor fuels, also to use the sensible heat of the reaction products as a method of distilling and fractionating an independent material such as crude or reduced crude.

55 A further object of the invention is to improve the process in respect to the manner of introducing the material to be cracked and of mixing this material and the heating gas.

60 In general, the preferred mode of executing the invention may be summarized as follows:

60 The oil to be cracked is introduced in a finely divided state, or in vapor form, or in the form of a fog or mist, into a stream of hot and preferably non-oxidizing gas, which may have been heated by some external means, but is preferably 65 hot combustion gases produced by the burning of fuel and air in a closed chamber adjoining the cracking chamber, or in a portion of the cracking chamber itself. The oil and the hot gas are quickly and intimately mixed so that the oil is 70 suddenly vaporized if in the form of a mist or fine articles, and thereupon quickly superheated, or is immediately superheated if it has been introduced in the form of vapor, to the determined cracking temperature. As a result of 75 rapid and thorough mixing, and the large or

infinite surface of contact, extremely rapid transfer of heat takes place between the heating medium of gas and the oil to be treated. The mixture of hot gas and superheated vapor is maintained, or continues to be, for a definite period 5 of time, at the predetermined cracking temperature, by virtue of continuous passage at the proper speed through the cracking chamber. The length of this reaction time has as a natural factor the volume of the cracking chamber, that is to say its length and width, and may be varied with precision within relatively wide 10 limits by varying the rapidity, otherwise not of absolute significance, with which the mixture of heating gas and oil vapor streams through the 15 cracking chamber.

The reaction time for virtually all portions of the vapors to be converted is controllable with an exactitude on the order of one one-hundredth of a second. The reaction temperature is readily 20 and exactly controlled by regulating the amount and temperature of the hot inert gas and/or by regulating the proportion and/or the degree of preheat of the hydrocarbon material fed in to be vaporized and/or superheated by the heating 25 medium and/or by regulating the extent of the vaporization and/or superheat of the hydrocarbon vapor fed in.

As the reaction mixture leaves the reaction chamber, the mixture is cooled to a temperature 30 at which substantially no cracking, or over-cracking, takes place, by complete and thorough mixing with a relatively cool oil. This quenching is practically instantaneous and precludes any overcracking. In general, the quenching material 35 constitutes the charging stock, to which may be added a cool heavy oil obtained from a later step in the process.

Following this quenching step, the resulting mixture of cooled reaction products, and any 40 vaporized quenching oil, and quenching oil which has not been vaporized, passes to an operation, which involves a thorough mixing of the gases and vapors with a hot liquid oil, which may or may not be identical with the oil left unvaporized 45 in the quenching step. A thorough and complete mixing is obtained between this hot oil and the products from the quencher by the use of spray nozzles. Any lampblack which may have been formed in the cracking operation and which in 50 itself is very difficult to wet is taken out of the gases at this point, or is largely taken out. Leaving the hot spray, the materials enter a separator which, by changing the direction of flow of these materials a plurality of times, and by exposing 55 to them liquid films, insures the removal of any mist or particles of heavy liquid or lampblack from the vapor and finally allows passage to a fractionating tower of clean vapor and gas.

In some cases the hot spray step may be 60 omitted and the liquid, gaseous and vaporous materials from the quencher may be delivered directly to a louvered separator or its equivalent. With such a separator, sufficient contact between the liquid and the gas and vapor can be obtained, 65 to remove heavy liquid particles and carbon particles, if any.

The material which is to be cracked is preferably the liquid material collected in an accumulator at the base of the fractionating tower or 70 elsewhere, that is, material which is in the liquid phase after leaving the quencher and the separator, or it may be reflux condensate material recovered from a plate in the fractionating tower, or a mixture of these two, or it may be a different 75

material as will be described later. This material may be introduced in the reaction chamber in any one of three ways. It may be introduced directly through atomizing nozzles in the form of liquid, such atomizing nozzles being preferably of a mechanical type although nozzles of the steam atomizing type may also be used. Again, the material to be cracked may be introduced in the form of vapor, and in such a case the material withdrawn from the fractionating tower is passed through a pipe still, after which it enters a vaporizer under reduced pressure, the vapors released passing through a separator to the nozzles of the reaction unit and the liquid material being recirculated or being withdrawn as will be described in detail later. The third method of introducing material to the cracking chamber involves the step of preheating the material to a relatively high temperature, vaporizing a portion of the material and using this vapor as a vehicle for the unvaporized material, the unvaporized material being carried in the form of a fine mist or fog, from which any large liquid particles are removed by a separating step. A modification of this form of feed is one in which preheated liquid is atomized in other vapor, or in a gas, to form, after separation, a stable fog.

The gas or heating material which is used for raising the material to be cracked to the reaction temperature is preferably an inert gas, that is, one that is non-oxidizing. More especially the process employs gases produced by complete combustion of air and practically as generated, and preferably generated in the same unit or immediately adjacent the mixing and reaction unit, these gases containing substantially no uncombined oxygen and being of a temperature upwards of at least 2500° F. In connection with some of the aspects of the invention, other suitable gases heated to a sufficient temperature might be utilized, for example, such as externally heated flue gases or externally heated fixed gases derived from the system, or similar gases obtained from other refining operations. For a definite volume of material to be converted, the temperature of the gas determines the amount necessary, since this gas must contain sufficient sensible heat at a high enough temperature so that when mixed with the material to be cracked the temperature of the entire mixture of heating gas and the hydrocarbon material is that which has been determined for carrying out of the reaction. The process permits of mixing very hot gases with the hydrocarbons to be converted, yet without danger of detrimental local overheating, and this is an important advantage since the amount of the gases to be mixed, to be quenched along with the vapors, and to be passed through the reflux fractionating, condensing and gas separating and absorption equipment is kept as small as possible. Besides heating inert gas externally, it is possible to form hot products of combustion of fuel and air outside of the reaction chamber and introduce these in the reaction chamber.

An important step for the successful operation of the process involves complete and instantaneous mixture of the hot gas and the material to be cracked. If the material to be cracked is fed to the reaction chamber in the form of a vapor or a mist or fine fog, as has been described, it has been found that the most satisfactory mixing which may be obtained results from the feeding of this material in the form of a thin sheet or stream, preferably a hollow cylindrical stream. The products of combustion are formed in an

annular space around the path of this stream and impinge radially on the material to be cracked. Such a mixing apparatus insures an intimate mixing of the heating gas and the material and substantially instantaneous temperature equilibrium without local overheating. In general, the temperature of vapor or mist or fog so fed should be in the neighborhood of 750/850° F., the temperature being determined by the refractoriness of the material; that is, if the material can be cracked easily the temperature at which it is permissible to feed the vapor is relatively low.

When liquid materials are fed to the reaction apparatus, it is desirable to feed the material in the form of a thin conical sheet which flares across the stream of the hot heating gases. The resulting turbulence insures instantaneous mixing of the materials and immediate attaining of the reaction temperature. The mixing may be accomplished either by the use of mechanically atomizing nozzles or by steam atomizing nozzles or by any other suitable method of atomization which will bring about the desired result.

The mixture of gases and material to be cracked travel at high velocity through the reaction chamber, the rate being dependent on the time of reaction desired.

For ordinary cracking, that is to say where conversion to lower-boiling products is wanted but formation of aromatic or like bodies is not particularly sought, the cracking temperature may range from about 700° to about 1000° F., depending upon the material treated and the degree of conversion desired, and likewise upon the reaction time, and the reaction time may range, consistently with other conditions, from a small fraction of a second up to several seconds or longer, but I wish to emphasize that the best results are obtainable with conditions adjusted to very brief reaction times, preferably less than one second.

In order to obtain a product having any material content of aromatics, it is necessary to employ in the process reaction temperatures upwards of about 900° F., and for the production of motor fuel having an excellent antiknock rating the temperature may range upwards of 950° F., and preferably not above 1400° F., though this is not necessarily an upper limit. Reaction temperatures can not be more definitely stated because there is a reciprocal relation between the factors of time and temperature, as I have demonstrated by passing a mixture of heating medium and hydrocarbon vapors from the point of commingling to the point of quenching so rapidly that, notwithstanding the hydrocarbons were exposed to a temperature far above the accepted cracking range, no alteration in the structure of the hydrocarbons was discoverable.

In cracking crudes, fuel oil or the like, the cracking temperature should be adjusted to avoid the deposition of coke or the formation of any material amount of lampblack. For the production of liquids having a low hydrogen-carbon ratio from such materials the cracking temperature should be above about 1050°. When products of a different composition are sought, the temperature may be considerably lower.

Dependent upon the other conditions, the reaction time for the production of aromatics or other anti-knock bodies should be brief. Such reaction times are accompanied by the best results. Reaction times that are most favorable are on the order of a fraction of a second to a

few seconds, and, better still, fractions of a second.

The cracking operation may be carried out below, at, or above atmospheric pressure. The use of pressures above atmospheric increases the yields and decreases the size of equipment required for a given throughput. Operating pressures in the order of about 50 pounds per square inch are economical for this process. In general, 10 the pressure selected is a matter of economic balance between yields to be obtained, the size and strength of the equipment and the cost of compressing the air and the fuel.

After the material to be cracked has been 15 maintained at the reaction temperature for a definite reaction time, it enters the quencher, where it is immediately mixed with a very fine spray of relatively cold material. The mixing to be obtained must be substantially instantaneous and this is insured by the very fine sub-division of the cooling material and the high velocity of the reaction products which impinge on and mix with the cooling material. The temperature is decreased to approximately 750° F. or as much 25 lower as may be necessary to insure that substantially no further cracking will take place, or to a temperature where a sufficient quantity of the quenching liquid remains in the liquid phase to balance the operation.

20 The quenching or cooling oil is in most cases the material to be charged to the unit. In case the amount of raw material and the cooling effect obtainable therewith are insufficient to reduce the temperature of the products of the reaction 25 below the reaction range, it is my purpose, as in the preferred form of the invention, to increase this cooling effect by the addition of cooled material from the fractionating tower, such as gas oil reflux or accumulator stock.

40 When crude oils are charged to the quencher, the excess heat contained in the products of reaction is used to distill the natural gasoline content of the crude oil as well as the kerosene and an appreciable amount of the gas oil contained 45 in the crude. The amount of the lower boiling material distilled is controlled by the temperature maintained in the quenching step. This step also serves to preheat the material to be converted.

In the cases in which distillates serve as the 50 material to be converted, it is advantageous to use this material to absorb gasoline contained in the gas leaving the fractionating equipment. After the absorption operation, the enriched oil is charged to the quencher and the heat contained 55 in the reaction products serves to distill out such gasolines. In this manner it is possible to recover the maximum amount of gasoline from the gaseous products of reaction and to eliminate any special distilling step for the removal of absorbed gasoline. Gas oil reflux may be taken 60 from the fractionating tower and cooled, and before being reintroduced in the quencher, it may be used for this absorbing operation. This is particularly beneficial when crude oils serve as 65 charging materials to the quencher, since such material is not adapted for the absorption of gasoline from gasoline rich gas.

70 However, any other suitable liquid, such as water, either alone or in admixture with the material to be converted, may be used for quenching. A portion, all or none of the quenching liquid may be vaporized. Usually, at least a considerable portion of the quenching liquid emerges from the quench unvaporized, and it is usually from this 75 unvaporized and heated quenching material that

the feed to the reaction zone is ultimately derived.

In the cracking of materials poor in hydrogen for the production of aromatic and desirable unsaturated hydrocarbons, it is important to produce light motor fuels containing relatively low percentages of hydrogen and to avoid as far as possible the production of fixed hydrogen or hydrogen-rich gases or liquids, since the formation of these from low-hydrogen materials necessitates the concomitant formation of large amounts of lampblack. By maintaining a temperature which favors the recomposition of the cracked constituents to form benzol and similar aromatic compounds, the amount of lampblack can be much reduced.

A specific novelty of this invention is the step of insuring the removal of lampblack from the material which has been cracked. In the cracking of heavy hydrocarbons poor in hydrogen for the production of low-boiling hydrocarbons, it is generally true that carbon will be formed since all low-boiling hydrocarbons, whether produced by decomposition or decomposition and recomposition, must contain a certain amount of hydrogen. When such materials poor in hydrogen are cracked, the formation of low-boiling hydrocarbons may necessitate the formation of some free carbon which appears in the reaction products in the form of lampblack. This material is always found in a very finely divided form and, as I have discovered, is very difficult to wet with oil and remove from the vaporous and gaseous mixture obtained from the reaction chamber. Unless a step in which these reaction products are treated for the removal of lampblack is introduced in the process, it is virtually impossible to deliver vapor to the fractionating step which is clean and which can be fractionated for long periods of time without causing plugging of the column due to deposited carbon. I have found that carbon or lampblack suspended in the products of the cracking reaction can be removed by introducing a hot liquid oil in a state of fine dispersion into the mixture of the reaction products and the quenching oil. In this manner the carbon is wetted and any fine droplets of heavy hydrocarbons are agglomerated, so that it is relatively easy to separate these from the vapor and deliver the vapor to the fractionating step free from any materials which would tend to interrupt the continuity of the operation. The liquid oil which is used for this scrubbing operation is the oil which accumulates at the base of the fractionating tower or elsewhere. This oil is practically identical with the oil which remains unvaporized in the quenching operation, since no heat is added to or withdrawn from the oil in passage from the quencher. The temperature of the oil so introduced is substantially the same as the temperature obtained in the quencher. Even in the operation to be described later, in which the gas oil reflux from the fractionating trays of the tower falls directly into the accumulator stock, the temperature is only slightly less than that obtained in the quencher, the extent of the difference depending on the amount of reflux pumped over the tower.

The mixture of unvaporized quenching material, scrubbing oil and gaseous reaction products which leaves the scrubber, is apt to contain fine droplets of heavy unvaporized material, wet particles of lampblack and similar materials, which, if allowed to enter the fractionating column without a previous separating step, would cause difficulty in the operation. An additional novelty in

this improved process involves the step of separating such materials from the vapor. The separator is preferably one containing louvers, which will insure a very tortuous passage for the mixture of gases, vapors and liquids as it passes through the separator so that the material to be removed as liquid will impinge on these louvers and agglomerate. These louvers are preferably arranged in banks so that they can be easily removed from the side of the separator for cleaning when such is necessary. From the separator a clean vapor is delivered to the base of the fractionating tower so that subsequent fractionation of the vapors may take place without any interruptions in the process. The removal of any liquid particles also insures a clean gas oil on the lower plates of the fractionating column. In some forms of this invention, this gas oil is withdrawn through reflux coolers to be recirculated to the quencher and by preventing any residual material from being carried up into the tower by the vapors, the operation of the cooling equipment used on the gas oil will be improved and higher heat transfer rates will be obtained since the transfer surface will not become fouled.

The various matters which constitute this invention will be apparent in the detailed description which follows.

In the accompanying drawings, forming a part hereof:

Fig. 1 is a vertical longitudinal section of one form of cracking unit with appurtenant apparatus;

Fig. 2 is a similar view of another form of cracking unit, parts being in elevation and the piping for supplying the feed nozzles being illustrated schematically;

Fig. 3 is a cross-section on the line 3—3 of Fig. 2;

Fig. 4 is a cross-section, on a larger scale, on the line 4—4 of Fig. 2;

Fig. 5 is a fragmentary longitudinal section on a still larger scale through one of the feed nozzles shown in Figs. 2 and 4; and

Figs. 6—11 are schematic views illustrating different forms of systems for carrying out the invention.

The cracking unit, two forms of which are illustrated, is designated generally by the reference character A.

The form shown in Fig. 1 is adapted for liquid feed, vapor feed or fog feed, by substitution of appropriate nozzles. The unit is encased in a metal shell 2, which is lined with thick walls 3 of refractory and heat-insulating materials, enclosing a combustion chamber 4, a mixing chamber 5, and a reaction chamber or tube 6. The mixing chamber may be considered as part of the reaction chamber. It is preferably enlarged in order to keep the hydrocarbon material, more particularly when it is introduced in liquid phase, from striking and coking on the walls, and when thus enlarged its forward portion 7 is contracted on a slope to join the reaction tube.

The combustion chamber is located in the entrance end of the unit, and is separated from the mixing chamber by a refractory bridge wall 8 containing a central, narrow-edge orifice 9. A wide entrance 10 at the back of the wall converges to this orifice to contract the stream of the hot combustion gases and increase their velocity as they pass from the combustion chamber to the orifice. Refractory filling 11 at the back of the mixing chamber is formed to provide reversely flaring surfaces extending out-

ward and forward to the walls which surround the largest diameter of the chamber. The flaring ends of the mixing chamber eliminate eddy or back-flow regions, which would tend to cause deposition of carbon. Since irregularities in the 5 operation of the system can not always be avoided and since some materials are particularly rich in carbon, the reaction or mixing chamber may be provided with removable plugs 12.

One or more burners 13 are carried by a rear 10 head 13a and deliver the mixture of air and fuel, the latter being preferably gas, into the combustion chamber. Pipes 14 and 15, provided with regulating valves 16 and 17, conduct the air and fuel gas under suitable pressure, the air and 15 fuel are mixed in accordance with known practice and the mixture is supplied to the burners as indicated.

One or more nozzles 18 introduce the oil as liquid, vapor or fog into the rear portion of 20 the reaction or mixing chamber. This nozzle may be disposed in various positions, but in the particular construction being described it is located in or near the orifice 9 and is designed to project a conical sheet or spray of the vapor 25 or liquid across the stream of hot gas, the abrupt intersection of the stream resulting in a quick and uniform mixing, with quick vaporization and/or superheating of the hydrocarbons to the converting temperature. In the case of liquid 30 feed, known mechanical atomizer nozzles of the whirling or centrifugal type are suitable. The supply line 19 leading to the feed nozzle may have a regulating valve 200, or the amount of material that is fed may be controlled by other 35 means.

A thermo-couple 45 held in a plug 12a projects into the reaction chamber, to afford a reading of the temperature therein.

Connected directly to the shell at the outlet 40 end of the reaction chamber is a small quenching chamber 20. This chamber contains one or more spray nozzles 21 of such character and disposition as to disperse quenching liquid in finely divided form, in intimate and thorough 45 contact with the entirety of the issuing mixture of gas and vapors, or as they may be termed for convenience, the reaction products. Mechanical atomizing nozzles of the centrifugal type are preferably employed in the quencher. 50

From the quenching spray, the reaction products and the unvaporized quenching liquid pass to scrubbing and separating apparatus forming part of the present invention. The precise form, constitution and arrangement of this apparatus 55 are susceptible of modification, but in the preferred embodiment a vertical cylindrical section 22 is connected directly to the bottom of the quencher, so that all of the products of the quench turn and pass down through this conduit, where they are intimately sprayed with hot oil dispersed by a series of atomizing nozzles 23, which are supplied with the hot oil by piping 24. This treatment wets any particles of lamp-black that may still be suspended in the gaseous 60 and vaporous reaction products after they pass through the quench, and causes some droplets of liquid hydrocarbons to coalesce.

The materials next pass to a separator 25, which is preferably connected directly beneath 70 the spray scrubber section. This separator comprises a much enlarged chamber in which the velocity of travel of the mixture is materially reduced so that droplets of heavy hydrocarbons resulting from either the quenching or the scrub- 75

bing spray fall or are thrown out of the vaporous and gaseous part and are gathered to the liquid part, at the same time that the wetted carbon particles are also taken out and held in the liquid body. Separation of fog and lampblack may be promoted in various ways, but the most effective apparatus for this purpose is one which compels the materials to change their direction of flow repeatedly in confined spaces, while presenting an extensive amount of surface on which the liquid portions can gather together and entrap carbon particles.

To this end the separator chamber is preferably equipped with banks of reversely inclined louvers 26, which divide the interior into zig-zag channels or narrow communicating interspaces. For the purpose of cleaning, the banks of louvers are preferably made removable.

The final separation of the body of liquid on the one hand and the clean vapors and gases on the other hand may be effected adjacent this separator, and the liquids and gaseous fluids may be conducted off separately to an accumulator and to fractionating equipment, respectively. Economy in construction, however, is to be realized by constructing a liquid accumulator tank 27 at the base of the reflux fractionating column 28, as shown in the schematic views, in which event all the liquid, gases and vapors, already separated as far as removal of fog and lampblack from the gases and vapors is concerned, are conducted through a large pipe 29 to said tank.

Before describing the system as a whole, in its several embodiments, the form of mixing and reaction unit shown in Figs. 2 and 3 will be taken up. This construction is particularly well adapted to heating and converting material which is fed in the form of either vapor or fog. As in the other example, the unit is built of refractory and insulating material 3 inside a metal shell 2. The combustion chamber 32 built in the entrance end of the unit surrounds a mixing tube 33 built of material such as carborundum brick in the form of a checker-work. This tubular checker-work may be supported at the middle in a bridge wall 34, so that two rings of checker brick are provided at opposite sides of the wall. One or more vapor or fog feed nozzles 35, supplied through pipes 51, for introducing the material to be converted, are disposed in line with the mixing tube, being supported in a removable rear head 37. The hydrocarbon vapor, or the exceedingly finely dispersed hydrocarbon liquid carried in vapor or gas, is consequently delivered at high velocity, and as it passes through the mixing tube this stream is abruptly intersected by streams of the hot combustion gases pouring inward through the openings in the checkerwork. Maximum turbulence and very rapid mixing and superheating and/or vaporizing of the material is the result. In both types of mixing, heating and reaction unit, the combustion chamber is carefully designed to insure complete combustion before the hot combustion products encounter the hydrocarbons.

The burners 39 (Fig. 3), supplied by valved air and fuel pipes 40, 41, open transversely into the combustion chamber 32, preferably from opposite sides, and preferably so disposed that their products impinge against surfaces of the bridge wall 34. The highest possible velocity is maintained on the combustion gases consistent with the permissible pressure drop in these gases as they enter the mixing tube or chamber, and the internal diameter of the mixing tube is kept as small as

possible, in order to insure the most rapid and thorough mixing.

The perfect mixture of the hydrocarbons in the vapor phase and of the heating gas issues from the mixing tube at the reaction temperature determined by the proportions, states and heat contents of the constituents that entered into the mixture, and at this temperature passes rapidly through the heat insulated reaction chamber 42, the volume of which, together with the rate at which the mixture is passed, determines the time during which the mixture is kept at the predetermined temperature. From the delivery end of the mixing tube, the reaction chamber expands to a much enlarged diameter and is thereafter contracted again to a tubular portion 43, to which the quencher 20 is connected. The expanding and contracting zones of the enlargement of the reaction chamber are flared and tapered, respectively, on gradual slopes or curves designed to suppress backflow or persistent eddy currents. The gradual expansion from the mixing tube prevents eddy currents being established at this region, and by so doing minimizes the formation of lampblack. The contraction of the downstream section of the reaction chamber is advantageous, since it is in this section that the production of a certain amount of lampblack may result from the reactions, for which reason it is desirable to maintain a high velocity through this section in order to sweep the fine carbon out of the reaction chamber into the quencher 20 and thence to the scrubber and/or separator that have already been described. The enlarged section of the reaction chamber has the advantage of reducing the over-all length of the reaction unit, without altering the condition of rapid, continuous flow of all portions of the mixture throughout the length of the reaction zone. If through any faulty control or functioning of some part of the system, or because of operating on material particularly disposed to carbon formation, an appreciable amount of carbon should be deposited in the reaction chamber, it will fall out in the expanded section, where it will not interfere with the operation. Under favorable conditions, the unit will operate indefinitely without the necessity for cleaning. If the necessity arises, the reaction chamber can be cleaned expeditiously and easily, on removing the plugs 44. The upper of these plugs is utilized as a holder for a thermo-couple 45^a for measuring the temperature in this part of the reaction chamber, and another thermo-couple 45^b is supported in a plug 47 in the contracted section.

The vapor or fog feed nozzles 35 embodied in either form of the mixing and reaction unit are of a construction to deliver a thin sheet stream of large surface. Compactness and effectiveness of mixing are best served by the use of nozzles that deliver hollow tubular streams of the vapor or fog. As illustrated in Figs. 4 and 5, a cylindrical nozzle body 58 is applied to the end of a nozzle pipe 51, and in this body there is a spider 52 which holds a forwardly projecting stem 53, to which is secured a disc 54 centered in the outlet end of the nozzle body, leaving an annular orifice 55 between the disc and the inner wall of the body. A single nozzle of this character will suffice, but for the plan of mixing utilized in Figs. 2 and 3 a considerable volume of feed with large stream surface can be secured by grouping a number of the hollow stream nozzles in the head 37, these nozzles being preferably arranged in circular series, and the nozzle bodies being supported

in a refractory plug 56. The several nozzles are supplied through a manifold pipe 51, and the individual nozzle pipes are provided with valves 58 (Fig. 2). The jets of hot combustion gases strike the group of vapor streams at right angles and from all sides, and the intermingling is exceptionally rapid.

Fig. 6 illustrates a preferred form of the complete equipment and process. In this operation the charging material is raised to a suitable pressure which may be in the neighborhood of 100 to 200 pounds per square inch by pump 60 and meets the enriched scrubbing oil passing by way of pipe 61 from absorption tower 62, which scrubbing oil has been raised to a suitable pressure equal to that mentioned above by pump 63. These two materials are mixed in pipe 59 or elsewhere, and enter quencher 20 through spray nozzles 21, at which point they are mixed intimately with the cracked products leaving the reaction chamber of cracking unit A. Naturally, instead of mixing these two quenching materials outside the quencher, they could be supplied to separate spray nozzles in the quencher. The vaporized and unvaporized feed material, the products of the reaction and the heating gas pass to scrubber 22, wherein they are intimately mixed with the accumulator stock which has collected in accumulator 27 and which has been raised to a suitable pressure by pump 64 and finally atomized by spray nozzles 23 after passing through pipe 65. At this point any lampblack is wetted out and the mixture of finely divided liquid, lampblack and vapors pass through separator 25 where louvers, vanes or baffles of suitable construction insure the separation and agglomeration of the small liquid particles held in the vapors. The vapors and liquids pass through pipe 29 and enter accumulator 21, at which point the liquids separate out while the vapors and gases pass upward through fractionating trays 66 in the column 28 in counter-current to the refluxing oil pumped over the top tray by pump 67. The vapors and gases from which the gas oil has been fractionated pass from the top plate of the tower through pipe 68 to condenser and cooler 69 and pass from there to gas separator 71. Gasoline or other liquid distillate is withdrawn from the side of the gas separator through pipe 72, and water, resulting from combustion, is withdrawn at the bottom through line 72a. Part of this may be taken as product I, while the remainder enters the suction of pump 67 to be returned through pipe 73 to the fractionating tower as the above-mentioned refluxing oil. The gas separated from the gasoline in separator 71 passes through pipe 74 to the base of tower 62 in counter-current to scrubbing oil, which may be the gas oil reflux obtained on the lower fractionating trays and transferred through pipe 75 by pump 76 to the top of tower 62. This reflux condensate coming from the fractionating column 28 passes through a reflux cooler 77, where its temperature is greatly lowered so that it is cold enough to serve as the absorbing liquid in the absorption tower 62 and as part of the quenching liquid in the quencher 20. An accumulator tank 78 may be connected in the reflux offtake piping.

If low cold test gas oil is charged, it may be substituted for the reflux gas oil in the absorption tower 62.

As the cooled gas oil passes down tower 62, it absorbs and removes gasoline contained in the gas, so that gas, free of gasoline, is removed by pipe 79 as product II. The enriched gas oil is

withdrawn from the base of tower 62 by pump 63 and is circulated to the quencher, as has been described.

The material withdrawn from the accumulator 27 at the base of the tower 28 by pump 64 is split and part of it is circulated through pipe 65 and scrubbing nozzles 23, the remainder passing through pipe 80 to enter pipe still 81 where the oil is raised to a temperature on the order of 750°-850° F. The pressure is reduced by valve 82 and the material enters vaporizer 83, in which enlarged zone the greater portion of material is flashed into vapor. The unvaporized material is recirculated to accumulator 27 through pipe 84. In the case when this material is particularly heavy or tarry, or in the case when it is desired to make substantial amounts of fuel oil, it may be withdrawn through cooler 86 as product III.

The vaporized material leaves vaporizer 83 through pipe 87 and enters separator 88, which serves to remove any entrained liquid material or liquid formed by condensation in line 87. These materials are withdrawn from the separator through pipe 90, and may be recirculated either to accumulator 27 or to separator 25. Separator 25 is placed very close to the reaction unit A, so that the vapors pass directly to nozzles 18 or 35. After passing through this nozzle or nozzles the vapors are intimately mixed with products of combustion from the burners, after which they pass through reaction chamber 6 for the desired length of time, after which they pass through quencher 20, as has been described.

In the case when it is desired to produce large quantities of fuel oil, it is possible to withdraw such material from accumulator 27 through pipe 92 and cooler 93 to form product IV. It will be seen that fuel oil may be produced at this point or as product III after passing through cooler 86, and in most cases it will not be desirable to produce such material at these two points but at either one or the other.

Gas oil may be drawn off from the system at the point marked product V.

This particular flow is of great value in that it insures continuous operation of the equipment without any difficulties due to coke formation at various points, which would cause intermittent operation. When little or no fuel oil is withdrawn, practically all of the charge will be converted into low-boiling hydrocarbons. This is particularly true when distillates are charged, for in such cases, only material which can not be ultimately vaporized in the pipe still is withdrawn as tar. This is a very small percentage of the material charged since, owing to the precision with which the reaction time and temperature can be controlled, the amount of polymerization leading to the formation of tar which occurs during the operation is very small and the production of tar may be practically eliminated. When charging residual containing materials, the fuel oil produced may also be held to a minimum since in the case where a fuel oil product is withdrawn from vaporizer 83, a definite amount of liquid phase cracking may take place in pipe still 81, where the conditions may be held such that the heavy materials are preferentially cracked, thus reducing the amount of tar and heavy material which can not be vaporized in vaporizer 83 and must be eventually withdrawn either through cooler 86 or cooler 93.

In case it is desired to feed liquid material through nozzles 18 to cracking chamber 6, the plan just described may be simplified. In such

a flow the material withdrawn from accumulator 27 is raised to a sufficient pressure by pump 64 and passes through line 94 directly to the nozzle 18. In this flow the pipe still 81, vaporizer 83 and separator 88 are eliminated, or bypassed, as well as the necessity for re-circulating liquid material to accumulator 27. As heavy material builds up in the equipment, it is withdrawn through pipe 92 and cooler 93 as a product. The remainder of the operation is the same as that already described.

Fig. 7 illustrates a method of feeding highly atomized, unvaporized material suspended in its own vapor. In this flow the material withdrawn from accumulator 27 is raised to a high pressure by pump 64 and passes through pipe 80 to enter pipe still 81, where it is raised to a suitable temperature. The pressure is then reduced by valve 82, and the oil enters vaporizer 83, where the low-boiling constituents are flashed off as vapors. These leave the vessel by pipe 100. The liquid material which is unvaporized leaves by pipe 101, and the vapors and liquid, both under relatively high pressure, enter a mixing and atomizing device 102, where the liquid material is broken up more or less into a very fine mist. The atomizer discharges into a pipe 103, which admits the vapor and vapor-borne liquid particles, together with any unatomized liquid, into separator 104, which is preferably of a tangential type. Any liquid material which is not broken up into sufficiently fine particles is separated out and withdrawn as liquid through pipe 105 connected to a second atomizer 106. The vapor and the suspended particles leave by pipe 107 to enter into the second mixing and atomizing device 106, where the liquid material is further broken down and the materials are then delivered through pipe 108 into a separator 109, which is similar to separator 104. Any large particles of liquid which remain after atomizer 106 are separated out here and are withdrawn through pipe 207 for recirculation either to separator 25 or accumulator 27. The vapor and finely atomized liquid which has thus been classified by repeated atomizing and separating steps passes from separator 109 directly to the feed nozzle 18 of the cracking unit. In this manner finely divided liquid of definite particle size may be carried in its own vapor and charged to the cracking reaction. This treatment prevents the possibility of large droplets entering the cracking chamber and insures a greater amount of feed in a suitable form at a definite temperature for the reaction. The description has shown a two-stage atomizing and separating treatment of the liquid material but this invention is not necessarily limited to this number of steps, since it is possible to use either one or more than two steps for the preparation of the liquid and vapor fog. In other respects the operation and equipment are the same as described under Fig. 6, with the exception that no fuel oil is withdrawn from vaporizer 83. In some cases it may be desirable to withdraw heavy material from line 207 through line 208 and cooler 209 as product III.

Fig. 8 illustrates a modification which is primarily adapted for the cracking of clean materials in any one of the three methods of feed which has been described. It is well adapted to the treatment of residual containing materials and in this method the low-boiling constituents are fed to the cracking reaction and the heavy residual-containing material which might cause difficulty in the cracking step, due to polymeriza-

tion and concomitant coke formation, is removed as fuel oil. In this operation hot liquid gas oil reflux from one of the lower fractionating trays 66 is withdrawn from the tower through a pipe 110 and reservoir 78 and raised to a suitable pressure by pump 64. It passes through pipe 80 and enters pipe still 81, where it is raised to a suitable temperature which will be on the order of 750/850° F. The pressure on the material is reduced after it leaves the pipe still by valve 82, and the material enters vaporizer 83, from which the vapors pass through pipe 87 to separator 88 for introduction to the cracking step. Unvaporized material is recirculated to accumulator 27 through pipes 90 and 84. The material in the 15 accumulator is withdrawn by pump 112 and part sent through pipe 65 to the nozzles of scrubber 22. Part of the gas oil reflux withdrawn from the lower plates of the fractionating column is withdrawn through a cooler 77 and circulated by 20 pump 64 through pipe 78 over absorption tower 62, to recover gasoline-like hydrocarbons from the fixed gases, and after being thus enriched, is circulated, as described in connection with Fig. 6, to join the charging stock supplied through 25 pipe 59 to the nozzles of the quencher 20.

If, instead of crude oil or other residual containing material, a distillate, such as gas oil, for example, is charged to the process, the material collecting in the accumulator 27 may be entirely 30 suitable for use in the absorption tower 62. In that event part of this material may be pumped by pump 112, or by another pump, through a pipe 114 and a cooler 115 to the pipe 78 leading to the top of the absorption column 62, or the 35 fresh feed may be pumped directly to the gas absorption tower, and thence to the quencher 20. If residual-containing material is charged to the process, it is advisable to take reflux distillate from the lower plates of the fractionating column 40 28, to serve as the absorption medium for scrubbing the fixed gases and as supplemental quenching medium in the quencher 20, since in such a case the heavy material in the accumulator 27 would make for a difficult absorption operation, 45 on account of its high viscosity at the absorption temperature.

Assuming residual-containing material to be the charging stock, tar or fuel oil is taken out of the system at one or both of the places marked 50 Product III and Product IV, respectively. Depending upon whether the charging stock is a residual-containing material or is a distillate, gas oil may be taken out of the system at one or other of the places marked Product IV and Product V.

As was described in connection with Fig. 6, the flow may be modified when it is desired to feed liquid material to the mixing, heating and reaction unit A. In such a case, pipe still 81, 60 vaporizer 83 and separator 88 will be bypassed or omitted, and the oil will be supplied directly by pump 64 through line 94 to the atomizing nozzle of the cracking unit. Likewise, the fog feed flow which was described in connection with Fig. 7 65 may be substituted in this or in any other of the embodiments of the process.

Fig. 9 shows a form of operation suitable for any type of charging stock. In this case the gas oil reflux formed in trays 66 is allowed to fall directly into accumulator 27, from which it is withdrawn by pump 64 and charged to the nozzles in the cracking unit through any one of the three methods of feed described; that is, either as a vapor, as a fog or as a liquid. Part of the ma- 75

terial withdrawn from accumulator 27 passes through pump 115 and reflux cooler 116. In the case of distillate charging stock, it is possible to use this material as an absorbing agent in tower 62. This material may also be withdrawn as a product, the nature of which is determined by the temperature maintained in the base of the fractionating tower, which in turn is directly dependent on the temperature obtained in the 10 quencher 20.

Fig. 10 shows a modification of the improved process, which is especially adapted for the cracking of selected raw materials, such as light gas oil or naphthas. It is particularly adapted for 15 improving the anti-knock qualities of the latter materials in that it is possible to take a naphtha of high detonating qualities and high boiling range and reform this material so that gasolines of high anti-knock properties and suitable boiling ranges are obtained. The sensible heat contained in the reaction products of such a cracking operation are used to distill the lighter fractions from a crude oil or similar material charged by pump 60 through line 59 to the quencher 20. 20 The material to be cracked, supplied through line 119, is raised to a suitable pressure by pump 120, passes through pipe 121 and heat exchanger 122, where it is preheated by gas oil withdrawn from one of the lower trays in the fractionating column. This material then passes through pipe 89 to pipe still 81, where it is raised to a temperature high enough to vaporize substantially all of the material after the pressure has been reduced by valve 82 and the material flashed in vaporizer 83. Any unvaporized material is withdrawn by pipe 84 and recirculated to accumulator 27. The 25 vapor leaves through pipe 87, enters separator 88, in which any entrained liquid and/or liquid condensed in the line are separated from the vapors to be recycled either to separator 25 or accumulator 27. The vapor passes to the cracking reaction, where the operation proceeds as has been described above. The reaction products enter quencher 20, and are cooled by raw material introduced by pump 60 and pipe 59 through spray nozzles in the quencher. This raw material is distinct from that charged by pump 120 and is preferably a crude although other materials may be used at this point. The rest of the operation is substantially similar to that described in the other cases. Fuel oil is withdrawn by pump 125 from accumulator 27. Part of this is used to scrub the quencher products in scrubber 22, the 30 remainder being withdrawn through cooler 127 and recovered as a product. In case additional preheat is desired in the material charged by pump 120, it is possible to recover some of the heat contained in the fuel oil withdrawn from the 35 accumulator, by heat exchange in a heat exchanger 128. The gas oil withdrawn from the tower through heat exchanger 122 passes through a cooler 129 and may be withdrawn as a product. It is also possible to withdraw through a pipe 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

fied for liquid feed to the cracking unit, as heretofore described.

Fig. 11 shows a further modification of the process which is particularly designed for the cracking of heavy residual material contained in the charging stock. Such a flow is particularly advantageous when it is desired to reduce the yield of fuel oil to a minimum. In this flow the material in the accumulator 27 is withdrawn and raised to a suitable pressure by pump 64, part of it being circulated through pipe 65 and the nozzles of scrubber 22, the remainder passing through pipe still 81, where it is raised to a temperature which will insure the vaporization of a substantial amount of the material. After the pressure is reduced by valve 82, the material flashes in vaporizer 83, vapors are withdrawn through pipe 135 and enter the base of the fractionating column 28, either below the trays or above a lower tray, for fractionation in fractionating trays 66. The liquid material is withdrawn from the vaporizer by line 136 and raised to a pressure in the order of 200 pounds per square inch by pump 137. It is then introduced into the atomizing nozzles of the reaction unit through line 138. The untreated residual-containing material is used as a quenching agent in quencher 20. Otherwise the operation is similar to those described above. Gas oil may be withdrawn through a cooler 77 as product V, and fuel oil or heavy tar which accumulates in accumulator 27 may be withdrawn through line 92 and cooler 93 as product IV.

In some operations sufficient separation may be obtained in the separator 25 to insure the delivery of clean vapors to the fractionating tower, in which event the scrubbing step (22) may be omitted.

I claim:

1. A continuous vapor-phase process for effecting thermal conversion of hydrocarbon oils, which comprises intimately mixing the material to be converted with hot gas and thereby heating the hydrocarbons to a predetermined converting temperature, conducting the mixture of gas and hydrocarbon vapor through a reaction chamber where conversion is effected, then immediately quenching the mixture sufficiently so that the reactions are definitely arrested, this being accomplished by spraying the mixture with cool oil, then spraying the mixture with hot oil the temperature of which approximates the temperature resulting from the quench, agglomerating fog particles and separating the same, together with any lampblack, from the gases and vapors, and only after this has been accomplished passing the vapors and gases to a reflux fractionating treatment.

2. A continuous vapor-phase process for effecting thermal conversion of hydrocarbon oils, which comprises intimately mixing the material to be converted with hot gas and thereby heating the hydrocarbons to a predetermined converting temperature, conducting the mixture of gas and hydrocarbon vapor through a reaction chamber where conversion is effected, then immediately quenching the mixture sufficiently so that the reactions are definitely arrested, this being accomplished by spraying the mixture with cool oil, collecting the liquid oil part of the materials that proceed from the quenching step, circulating this hot oil and introducing it in intimate contact with the gases and vapors passing from the quenching operation, and only after this passing the clean vapors and gases to a reflux fractionation treatment.

3. A continuous vapor-phase process for effecting thermal conversion of hydrocarbon oils, which comprises intimately mixing the material to be converted with hot gas and thereby heating the hydrocarbons to a predetermined converting temperature, conducting the mixture of gas and hydrocarbon vapor through a reaction chamber where conversion is effected, then immediately, by direct and intimate contact with cool oil, quenching the mixture sufficiently so that the reactions are definitely arrested, then thoroughly spraying the effluent from the quenching step with hot oil and thereby wetting any particles of lampblack present in the effluent, then conducting the mixture of gases, vapors and unvaporized quenching liquid in a tortuous course until fog particles present in the vapors and gases have been agglomerated and wetted carbon particles have been caught in the liquid, then separating the vapors and gases from the liquid, and only after these steps passing the vapors and gases to a reflux fractionating treatment.

4. A continuous vapor-phase process for effecting thermal conversion of hydrocarbon oils, which comprises intimately mixing the material to be converted with hot gas and thereby heating the hydrocarbons to a predetermined converting temperature, conducting the mixture of gas and hydrocarbon vapor through a reaction chamber where conversion is effected, then immediately quenching the mixture sufficiently so that the reactions are definitely arrested, this being accomplished by spraying the mixture with cool oil, then spraying the quenched gases and vapors with hot oil the temperature of which approximates that resulting from the quench, after which the gases and vapors are passed to a reflux fractionating treatment, utilizing as part of the quenching medium the charging stock from which the feed of material to be converted is ultimately derived, withdrawing liquid from a stage of the process after the spraying with hot oil following the quench, cooling it and re-circulating it to serve as additional quenching medium in the foregoing quenching step.

5. A continuous vapor-phase process for effecting thermal conversion of hydrocarbon oils, which comprises intimately mixing the material to be converted with hot gas and thereby heating the hydrocarbons to a predetermined converting temperature, conducting the mixture of gas and hydrocarbon vapor through a reaction chamber where conversion is effected, then immediately quenching the mixture to a temperature at which the reactions are definitely arrested, supplying the entirety of the charging stock, previously unheated, to serve as part of the quenching medium, passing the quenched gases and vapors to a reflux fractionating treatment, collecting the hot liquid oil that proceeds from the quenching step, deriving from this oil the feed of material to be converted, withdrawing reflux from the reflux fractionating treatment, cooling this reflux and re-circulating it to serve as additional quenching medium in the foregoing step.

6. A continuous vapor-phase process for effecting thermal conversion of hydrocarbon oils, which comprises intimately mixing the material to be converted with hot gas and thereby heating the hydrocarbons to a predetermined converting temperature, conducting the mixture of gas and hydrocarbon vapor through a reaction chamber where conversion is effected, then immediately quenching the mixture sufficiently so that the reactions are definitely arrested, this being ac-

complished by spraying the mixture with cool oil, then spraying the quenched gases and vapors with hot oil the temperature of which approximates that resulting from the quench, after which the gases and vapors are passed to a reflux fractionating treatment, supplying charging stock to serve as part of the quenching medium, collecting the liquid oil that proceeds from the hot spraying step, withdrawing a portion of this oil, cooling it and recirculating it to serve as additional quenching medium in the foregoing quenching step, and deriving from the reflux from the fractionating treatment the feed of material to be converted.

7. A continuous vapor-phase process for effecting thermal conversion of hydrocarbon oils, which comprises intimately mixing the material to be converted with hot gas and thereby heating the hydrocarbons to a predetermined converting temperature, conducting the mixture of gas and hydrocarbon vapor through a reaction chamber where conversion is effected, then immediately quenching the mixture to a temperature at which the reactions are definitely arrested, supplying the entirety of the charging stock, previously unheated, to serve as part of the quenching medium, passing the quenched gases and vapors to a reflux fractionating treatment, collecting in an accumulator stock the liquid oil that proceeds from the quench, delivering the entire reflux from the fractionating treatment to this accumulator stock, deriving from this stock the feed of material to be converted, and recirculating a portion of this stock, after cooling, to serve as additional quenching medium in the foregoing quenching step.

8. A continuous vapor-phase process for effecting thermal conversion of hydrocarbon oils, which comprises intimately mixing the material to be converted with hot gas and thereby heating the hydrocarbons to a predetermined converting temperature, conducting the mixture of gas and hydrocarbon vapor through a reaction chamber where conversion is effected, then immediately quenching the mixture to a temperature at which the reactions are definitely arrested, utilizing as part of the quenching medium the charging stock from which the feed of material to be converted is ultimately derived, passing the quenched mixture of vapors and gases to a reflux fractionating treatment, condensing and recovering light vapors that pass from this treatment, passing the gases through an absorption zone, withdrawing oil from a stage of the process after the quench, cooling this oil, passing it as an absorption agent through the absorption zone, and utilizing this oil, enriched with volatile hydrocarbons taken from the gases, as additional quenching medium in the foregoing quenching step, wherein the volatile constituents are vaporized.

9. A continuous vapor-phase process for effecting thermal conversion of hydrocarbon oils, which comprises intimately mixing the material to be converted with hot gas and thereby heating the hydrocarbons to a predetermined converting temperature, conducting the mixture of gas and hydrocarbon vapor through a reaction chamber where conversion is effected, then immediately quenching the mixture to a temperature at which the reactions are definitely arrested, utilizing as part of the quenching medium the charging stock from which the feed of material to be converted is ultimately derived, passing the quenched mixture of vapors and gases to a reflux

- fractionating treatment, condensing and recovering light vapors that pass from this treatment, passing the gases through an absorption zone, withdrawing reflux oil from the fractionating treatment, cooling this reflux oil, passing it as an absorption agent through the absorption zone, and utilizing this enriched liquid as additional quenching medium in the foregoing quenching step, wherein the volatile constituents taken from the gases are vaporized.
10. A continuous vapor-phase process for effecting thermal conversion of hydrocarbon oils, which comprises intimately mixing the material to be converted with hot gas and thereby heating the hydrocarbons to a predetermined converting temperature, conducting the mixture of gas and hydrocarbon vapor through a reaction chamber where conversion is effected, then immediately quenching the mixture to a temperature at which the reactions are definitely arrested, utilizing as part of the quenching medium the charging stock from which the feed of material to be converted is ultimately derived, this charging stock containing low-boiling hydrocarbons, passing the quenched mixture of vapors and gases to a reflux fractionating treatment, condensing and recovering light vapors that pass from this treatment, passing the gases through an absorption zone, collecting the liquid oil that proceeds from the quenching step, and recirculating at least a portion of this oil, after cooling, through the absorption zone, where it absorbs volatile constituents from the gases and thence to the foregoing

quenching step, wherein the volatile constituents taken from the gases are vaporized.

11. A continuous vapor-phase process for effecting thermal conversion of hydrocarbon oils, which comprises intimately mixing the material to be converted with hot gas and thereby heating the hydrocarbons to a predetermined converting temperature, conducting the mixture of gas and hydrocarbon vapor through a reaction chamber where conversion is effected, then immediately quenching the mixture to a temperature at which the reactions are definitely arrested, utilizing as part of the quenching medium the charging stock from which the feed of material to be converted is ultimately derived, this charging stock containing low-boiling hydrocarbons, passing the quenched mixture of vapors and gases to a reflux fractionating treatment, condensing and recovering the light vapors that pass from this treatment, passing the gases through an absorption zone, withdrawing oil from a stage of the process after the quench, cooling this oil, passing it as an absorption agent through the absorption zone, and utilizing this oil enriched with volatile hydrocarbons taken from the gases as additional quenching medium in the foregoing quenching step, wherein said volatile hydrocarbons, together with the low-boiling hydrocarbons contained in the charging stock, are vaporized and blend with the conversion products coming from the reaction chamber.

ERNEST WAYNE REMBERT.
